UNITED STATES PATENT OFFICE.

CROMWELL A. B. HALVORSON, JR., OF SAUGUS, AND LLOYD O. INGALLS, OF LYNN,
MASSACHUSETTS, ASSIGNEES TO GENERAL ELECTRIC COMPANY, A CORPORATION
OF NEW YORK.

HEADLIGHT.

1,143,539.

Specification of Letters Patent. Patented June 15, 1915.

Application filed November 25, 1911. Serial No. 662,451.

To all whom it may concern:

Be it known that we, CROMWELL A. B. HALVORSON, Jr., a citizen of the United States, residing at Saugus, county of Essex, State of Massachusetts, and LLOYD O. INGALLS, a citizen of the United States, residing at Lynn, county of Essex, State of Massachusetts, have invented certain new and useful Improvements in Headlights, of which the following is a specification.

Our invention has reference to a headlight and particularly, though not necessarily, to a headlight employing luminous or flaming electrodes, from which are evolved solidifiable products of combustion, which form a deposit when brought into contact with a condensing surface. When such solidifiable products are permitted to come into contact with the operating mechanism of the headlight, a deposit is formed thereon, thus interfering with the operation of such mechanism. In our headlight, we overcome this difficulty by dividing the space inclosed by the casing of the headlight into two separate chambers. In one chamber are located the arcing electrodes, suitable provision being made to conduct the fumes from the headlight. The operating mechanism for the lamp is located in the other chamber and is suitably connected to the electrodes or one of them through the partition between the chambers, which partition prevents the solidifiable products of combustion evolved at the arc from coming into contact with the operating mechanism and from being deposited thereon, and as the partition is made from a material having a fairly high permeability it shields the operating mechanism from the intense heat of the arc, and the arc itself from the magnetic influence of the operating magnet.

Our invention also comprises a novel form of casing which permits ready access to both the arc chamber and the chamber in which the operating mechanism is located.

Other novel features of our invention will appear in the following description and will be particularly pointed out in the claims.

Referring to the drawings, Figure 1 is a perspective view, showing the body of the headlight swung away from the back plate, against which it is normally seated, to afford access to the rear chamber containing the operating mechanism; Fig. 2 is a like view of the front door, to which is secured the

lens, swung away from the body of the headlight to afford access to the front chamber in which the electrodes are disposed; Fig. 3 is a vertical section, and Fig. 4 is a top plan view of our improved headlight.

The headlight is carried by a back plate 1 which also, when the headlight is in operating condition, closes the rear chamber of the headlight. The back plate 1 is secured to a stationary part 2 of the vehicle by straps 3. The electrodes and the operating mechanism therefor are mounted within a substantially cylindrical casing 4 hinged to the back plate 1 at 5. The front of the headlight is closed by an annular plate 6 hinged to the casing 4 at 7. This plate may conveniently be secured in position by a spring-pressed plunger 8, Fig. 3, which is received in an opening 9 in the casing. The plunger may be withdrawn and the door lifted by means of a handle 10. A lens 11 of any usual construction is secured in the annular plate 6. The headlight is divided into front and rear chambers 12 and 13 by a vertical partition 14, which, if the casing is made by casting, is preferably cast integral therewith. Viewed from above, as shown in Fig. 4, the two lateral parts 14^a of this partition are relatively near the front of the headlight in order to afford room for the operating mechanism of the lamp in the rear chamber, while the middle portion is curved toward the back of the headlight at 15 to afford room for the electrodes in the front chamber of the headlight. We have shown our invention embodied in a headlight of the luminous type, that is, in which the electrodes are made of materials suitable for yielding an arc having luminous vapors. The upper, positive electrode 16 is or may be formed of a bar of a material of such a character that it is but slowly consumed and is, in fact, known in the art as a non-consuming electrode. Copper is suitable for this purpose. This electrode is secured to the partition 14 by a clamp 17. The lower electrode 18 is or may be formed of a magnetite mixture. This electrode is carried by an arm 19 secured to a short shaft 20 passing through the partition 14. This shaft is supported in position at one end by a boss 21 formed upon the partition, (see Fig. 1), while its opposite end passes through and is supported by a strap 22 secured upon the partition 14 in the front chamber 12.

The operating mechanism of the lamp comprises a magnet 23 mounted on a stationary yoke piece 24. The armature 25 of the magnet is connected to a clutch member 26, which embraces a rod 27. This rod is guided below by a plate 28, while its upper end is pivotally connected to the outer end of the horizontal arm of an elbow lever 29. The other arm 30 of this lever is connected by a link 31 to the outer end of an arm 32, which is secured to the shaft 20 at the end opposite that to which the arm 19 is secured.

The circuit for the headlight is closed by a plug switch 33, which is connected to a spring contact 34 secured on the back plate 1 by a conductor 35. This contact engages, when the body of the headlight is closed against the back plate, a contact 36, which is in turn connected to the operating magnet 23 by a conductor 37. The other terminal of the magnet is connected by a conductor 38 to the upper electrode, the lower electrode being grounded through the casing of the headlight.

25 The top of the cylindrical casing 4, above the front chamber 12 is provided with an opening 39 communicating with a chamber 40 formed on top of the casing 4 by a wall 41 upstanding from the casing. This chamber is covered by a lid 42, which may be hinged at 7, and the cover is provided with a cowl 43 by which the fumes from the chamber 40 escape. The headlight has a bail 44 of any usual construction and legs 45 and 25 46 for maintaining the headlight in an upright position when it is removed from the vehicle.

The operation of our headlight is as follows:—When the magnet 23, is energized, 40 its armature is attracted, thereby lifting the rod 27 and the horizontal arm of the elbow lever 29. The lower end 30 of this elbow lever is then moved to the left, as viewed in Fig. 1, and the arm 31 imparts to the 45 shaft 20 a counter clockwise rotation. The arm 19 is thereby moved downwardly and the lower electrode 18 separated from the upper electrode 16, thus establishing the arc. The lower electrode is held in this position 50 and the arc continues until the circuit is in-

terrupted by the trolley passing over a length of insulation in the trolley wire, in accordance with ordinary practice, or until the circuit is otherwise interrupted and the magnet deenergized. The armature of the magnet is then released, together with the parts connected thereto, and the lower electrode brought into engagement with the upper electrode, and when the circuit is again closed the cycle of operations is repeated.

What we claim as new and desire to secure by Letters Patent of the United States, is,

1. In an arc headlight, a partition integral with the casing dividing the headlight into front and rear chambers, electrodes located in the front chamber, removable means for closing the ends of said chambers, operating mechanism located in the rear chamber, connections between the operating mechanism and the electrodes, and means for evacuating the fumes evolved from the arc from the front chamber.

2. In an arc headlight, a partition dividing the headlight into front and rear chambers, the electrodes being located in one chamber and the operating mechanism therefor in the other, a plate for closing the rear chamber and provided with means for supporting the headlight, and a door comprising a lens for closing the front chamber.

3. In an arc headlight, a partition dividing the headlight into front and rear chambers the electrodes being located in the front chamber and the operating mechanism therefor in the rear chamber, a back plate provided with means for securing the same to the vehicle, means for pivotally attaching the headlight to the back plate, and a front chamber comprising a lens for closing the front chamber.

In witness whereof, we have hereunto set our hands this twenty-fourth day of November 1911.

CROMWELL A. B. HALVORSON
LLOYD O. INGALLS.

Witnesses:

JOHN A. McMANUS, JR.,
FRANK G. HATTIE.

It is hereby certified that in Letters Patent No. 1,143,539, granted June 15, 1915, upon the application of Cromwell A. B. Halvorson, jr., of Saugus, and Lloyd O. Ingalls, of Lynn, Massachusetts, for an improvement in "Headlights," errors appear in the printed specification requiring correction as follows: Page 2, line 6, after the comma, insert the words *removable means for closing the ends of said chambers*; same page, lines 67-68, cancel the words "removable means for closing the ends of said chambers"; and that the said Letters Patent should be read with these corrections therein that the same may conform to the record of the case in the Patent Office.

Signed and sealed this 6th day of July, A. D., 1915.

[SEAL.]

R. F. WHITEHEAD,

Acting Commissioner of Patents.
